CHILD CARRIER FOR BICYCLE

John Peter Ronvik, Palos Heights, and Irvin E. Berger,
Skokie, Ill., assignors to Sears, Roebuck and Co., Chi-
cago, Ill.

Filed Feb. 4, 1974, Ser. No. 439,337

Term of patent 14 years

Int. Cl. D6—01

U.S. Cl. D6—48

Fig. 2.

Fig. 3.

Fig. 4.

Fig. 5.

FIG. 1 is a front perspective view of a child carrier for bicycle showing our new design;

FIG. 2 is a top plan view thereof;

FIG. 3 is a side elevational view thereof;

FIG. 4 is a rear perspective view thereof; and

FIG. 5 is a side elevational view thereof showing its use with a bicycle, with the bicycle and supporting bracket being shown in broken lines for illustrative purposes only.

We claim:

The ornamental design for a child carrier for bicycle, as shown and described.
